US0D1073769S

(12) **United States Design Patent** (10) Patent No.: **US D1,073,769 S**
(45) Date of Patent: ** May 6, 2025

(54) **CAMERA LENS**

(71) Applicant: **KOWA COMPANY, LTD.**, Nagoya (JP)

(72) Inventor: **Jun Takayama**, Soka (JP)

(73) Assignee: **Kowa Company, Ltd.**, Nagoya (JP)

(**) Term: **15 Years**

(21) Appl. No.: **35/519,160**

(22) Filed: **Dec. 1, 2022**

(80) **Hague Agreement Data**

Int. Filing Date: **Dec. 1, 2022**

Int. Reg. No.: **DM/226179**

Int. Reg. Date: **Dec. 1, 2022**

Int. Reg. Pub. Date: **Dec. 1, 2023**

(51) **LOC (15) Cl.** **16-01**

(52) **U.S. Cl.**

USPC **D16/219**

(58) **Field of Classification Search**

USPC D16/136, 206, 211, 216-220, 237;
